CLAIM

The ornamental design for a car wireless MP3 player, as shown and described.

DESCRIPTION

FIG. 1 is a front, top, right-side perspective view of the car wireless y player;

FIG. 2 is a rear elevational view thereof; and

FIG. 3 is a top plan view thereof;

FIG. 4 is a right-side elevational view thereof, the left-side elevational view (not provided) being a mirror image thereof;

FIG. 5 is a front elevational view thereof;

FIG. 6 is a bottom plan view thereof.

FIG. 7 is a rear, top, right-side perspective view of a second embodiment of the car wireless MP3 player, shown in an alternate bent configuration;

FIG. 8 is a rear elevational view thereof; and

FIG. 9 is a top plan view thereof;

FIG. 10 is a right-side elevational view thereof, the left-side elevational view (not provided) being a mirror image thereof;

FIG. 11 is a front elevational view thereof; and,

FIG. 12 is a bottom plan view thereof.

The broken lines depict unclaimed parts of the MP3 player, and thus form no part of the claimed design.

1 Claim, 12 Drawing Sheets
